PASSENGER VEHICLE

Robert H. Gurr, Costa Mesa, Calif., assignor to Wed Enterprises, Inc., Glendale, Calif., a corporation of California

Filed Sept. 6, 1966, Ser. No. 3,751

Term of patent 14 years

(Cl. D14—3)

FIG.1

FIG. 3

FIG. 4

FIG. 1 is a perspective view of a passenger vehicle showing my new design;

FIG. 2 is a top plan view thereof;

FIG. 3 is an elevational view of the side opposite that shown in FIG. 1;

FIG. 4 is a front end elevational view thereof, the rear end elevational view thereof is identical and therefore omitted for brevity.

I claim:

The ornamental design for a passenger vehicle, substantially as shown and described.
